UNITED STATES PATENT OFFICE.

MARIE AUGUSTIN NORMAND, OF HAVRE, FRANCE, ASSIGNOR TO ATELIERS ET CHANTIERS AUGUSTIN NORMAND, OF HAVRE, FRANCE, A CORPORATION OF FRANCE.

PETROL-HEATED STEAM-GENERATOR.

No. 926,958.

Specification of Letters Patent.

Patented July 6, 1909.

Application filed October 12, 1908. Serial No. 457,423.

To all whom it may concern:

Be it known that I, MARIE AUGUSTIN NORMAND, a citizen of the French Republic, residing at Havre, Department of the Seine-Inférieure, in France, have invented certain new and useful Improvements in Petrol-Heated Steam-Generators; and I do hereby declare the following to be a full, clear, and exact description of the invention, such as will enable others skilled in the art to which it appertains to make and use the same.

The present invention has for its object a special arrangement of the burners and of the combustion chamber for heating steam generators of the type termed vertical tube steam generators by means of petrol.

In the accompanying drawings: Figure 1 represents a longitudinal section of the steam generator. Fig. 2 is a front elevation, half in section and half in elevation.

The steam generator which is represented solely by way of example in the accompanying drawings is of the type which comprises two lower collectors connected with an upper collector by means of two nests of tubes.

The bottom of the combustion chamber 1 is constituted by a lower hearth 2 formed of joined bricks. The lateral walls of this chamber are formed by those tubes 3 (arranged back to back or otherwise, of the row of each nest of tubes which are most exposed to the flames. The lower part of the lateral walls is formed of brickwork in the usual manner. Apertures enabling the hot gases to enter the nests of tubes are provided in the lateral walls constituted by the tubes.

A brick partition 4 may be arranged between the nests of tubes at the upper part of the combustion chamber to form the roof thereof.

In the front of the steam generator, burners 5 are arranged; they inject petrol into the frusto-conical nipples 6—6 which communicate with the combustion chamber.

The air supply is taken through the front part of the frusto-conical chambers and by openings 7 formed in their lateral walls.

The nipples 6 are surrounded by a casing 8 which is provided with a number of swing doors 9. These doors open owing to the internal vacuum or reduction of pressure and permit of the passage of the air which enters the chambers 6 in order to maintain the combustion of the petrol.

The rear wall of the combustion chamber is constituted by a wall 10 in which a certain number of orifices 11 are formed. By means of this arrangement an air circulation is produced which cools the walls of the combustion chamber and insures the mixing of the combustion gases.

The casing 8 is located entirely outside of the combustion chamber and communicates with the latter only through the perforations 7 with which the nipples 6, applied to the front wall of the combustion chamber, are provided. These nipples are entirely inclosed by the casing 8, which forms an air chamber by which the supply of air to the burners is assured, the combustion itself not taking place within this chamber, but within the nipples and the combustion chamber with which the latter communicate.

The preceding description refers by way of example to a steam generator which receives the necessary air from the surrounding atmosphere. The invention is however also applicable to cases in which air under pressure is supplied directly to the steam generator; in this case the casing 8 is placed in communication with the compressor in any convenient manner.

The arrangement of the reservoirs or collecting drums, of the tubes and of the chimney may vary widely from that represented in the accompanying drawings.

I claim:

1. In a steam generator, the combination of a combustion chamber, a nipple directly applied to and extending from one wall of said chamber and communicating directly with the latter, said nipple being provided with perforations in its side wall by which air is conducted into the combustion chamber, a burner extending into the nipple and an air chamber inclosing said nipple and which supplies the same with air by means of said perforations.

2. In a steam generator, the combination with the combustion chamber, of a nipple applied directly to one wall of said chamber and provided in its side wall with a plurality of perforations forming air inlets through which air passes into said chamber, an air chamber inclosing the nipple, and a burner supported by the front wall of said air chamber and entering the nipple.

3. The combination with a combustion chamber, and a perforated nipple extending

therefrom, of an air chamber inclosing the nipple and provided with a swinging door which opens under the influence of a vacuum in the air chamber, and a burner coöperating 5 with the nipple.

4. In a steam generator, the combination with the combustion chamber, of a nipple applied directly to one wall of said chamber and provided in its side wall with a plurality 10 of perforations forming air inlets through which air passes into said chamber, an air-chamber casing applied directly to the wall of the combustion chamber and inclosing said nipple, said casing being provided in its front 15 wall with means to admit air, and a burner coacting with said nipple.

5. In a steam generator, the combination with the combustion chamber, of a plurality of nipples applied to one wall of said chamber and provided with perforations forming air 20 inlets through which air passes into said chamber, burners coacting with the several nipples, and an air-chamber casing applied to said wall of the combustion chamber and which incloses all of said nipples and supplies 25 the same with air.

In testimony whereof I affix my signature, in presence of two witnesses.

MARIE AUGUSTIN NORMAND.
